UNITED STATES PATENT OFFICE.

VERNON O. KARN, OF HOLLANSBURG, OHIO.

RAILROAD-TIE AND RAIL-FASTENING MEANS.

1,232,565.

Specification of Letters Patent.

Patented July 10, 1917.

Application filed October 9, 1916. Serial No. 124,606.

To all whom it may concern:

Be it known that I, VERNON O. KARN, a citizen of the United States, residing at Hollansburg, in the county of Darke, State 5 of Ohio, have invented a new and useful Railroad-Tie and Rail-Fastening Means; and I do hereby declare the following to be a full, clear, and exact description of the invention, such as will enable others skilled 10 in the art to which it appertains to make and use the same.

This invention relates to an improved railroad tie and rail fastening means, and one of the objects of the invention is to provide 15 an invertible railroad tie, to either side of which a rail fastening means may be attached.

A further object of the invention is to provide a hollow metallic tie having two of 20 its opposing faces provided with corresponding over-hanging flanges, whereby the tie may be inverted, so that the fastening means may be mounted and connected to either of said opposing faces.

25 A further object of the invention is to provide a rail fastening means consisting of a plate having opposite hooked ends to engage the flanges of either face of the tie, whereby the plate may be adjusted on the tie, there being ears on said plate between 30 which a rail clamping lever is pivotally mounted, said lever having means for holding the lever in contact with the base of the rail.

35 In practical fields, the details of construction may necessitate alterations falling within the scope of what is claimed.

The invention comprises further features and combination of parts, as hereinafter set 40 forth, shown in the drawings, and claimed.

In the drawings:

Figure 1 is a view in perspective of the improved railroad tie and rail fastening means, constructed in accordance with the 45 invention.

Fig. 2 is a longitudinal sectional view on line 2—2 of Fig. 1 showing parts in elevation.

Fig. 3 is a sectional view on line 3—3 50 of Fig. 1.

Referring more especially to the drawings, 1 designates a metallic railroad tie, which is hollow, and substantially rectangular in cross section, the opposing faces 2 and

3 of which are provided with lateral flanges 55 4. The flanges 4 from the face 3 extend toward the opposite flanges 4. Each rail fastening means consists of a plate 5, the opposite ends of which curve downwardly and upwardly, thereby forming the hooks 6, 60 which may engage over and under any two corresponding flanges 4, so as to hold the plate 5 to the tie, that is, against upward displacement. Upon reading the drawing, it is clearly obvious that the plate 5 may be 65 arranged upon either face portion 2 or 3 of the tie. Each plate 5 is provided with upstanding ears 7, between which, upon a suitable pin 8, a lever 9 is pivotally mounted. One end of the lever is constructed corre- 70 spondingly to and designed to fit the base of the rail. In other words, this end constitutes a gripping jaw 10. The other end of the lever is provided with a threaded eye 11, in which the set bolt 12 is threaded, there 75 being lock nuts 13, to hold the bolts in adjusted positions. When the rail is placed in position the opposing jaws of the levers are disposed in engagement with corresponding opposing parts of the base of the rail, the 80 plates 5 having been adjusted, after which the bolts 12 are adjusted, so that their lower extremities 14 will contact with the face of the tie. The bolts are adjusted sufficiently, to force the jaws 10 closely in contact with 85 the base of the rail, thereby securely holding the rail in position.

The invention having been set forth, what is claimed as new and useful, is:

1. In combination with a railroad tie having laterally and downwardly extending longitudinal side flanges, a plate having its ends provided with hooks extending over and hooked under said flanges, and rail clamping means carried by said plate to hold 95 the rail on the tie, said means comprising a pair of ears on said plate, a lever pivoted between the ears and having a clamping jaw at one end to engage the base of the rail, the other end of the lever having a set screw 100 threaded therethrough to contact with the tie, to force the clamping jaw in engagement with the base of the rail, and means for locking the set screw after having been adjusted.

2. In combination with a railroad tie having two of its opposing faces provided with laterally extending flanges, the flanges of

one face extending toward the flanges of the other face, whereby the tie may be inverted, a plate having means for engaging the flanges of either of the faces and provided with means for clamping a rail on the tie.

In testimony whereof I have signed my

name to this specification in the presence of two subscribing witnesses.

VERNON O. KARN.
